UNITED STATES PATENT OFFICE.

DANA BERG, OF FORT COLLINS, COLORADO.

SOUND BOX FOR PHONOGRAHS.

Application filed August 10, 1922. Serial No. 530,934.

To all whom it may concern:

Be it known that I, DANA BERG, a citizen of the United States, residing at Fort Collins, in the county of Larimer and State of Colorado, have invented a new and useful Sound Box for Phonographs, of which the following is a specification.

This invention relates to sound boxes for phonographs and more especially to the mounting of the stylus bar, one of the objects of the invention being to so connect the stylus bar to the diaphragm as to insure purity of reproduction, greater volume of sound than ordinarily, and substantial elimination of the harsh secondary tones so noticeable where the ordinary sound boxes are employed.

With the foregoing and other objects in view, which will appear as the description proceeds, the invention consists of certain novel details of construction and combinations of parts which will be hereinafter more fully described and pointed out in the claim, it being understood that various changes may be made in the construction and arrangement of the parts within the scope of the claim.

In the accompanying drawings the preferred form of the invention has been shown in said drawings.

Figure 1 is an elevation of a sound box having the present improvements combined therewith.

Figure 2 is a section on line 2—2, Figure 1.

Referring to the figures by characters of reference, 1 designates the usual sound box structure having a diaphragm 2 secured therein in any preferred manner. A stylus holder 3 is movably connected to the sound box by bearing members 2' and fixed relative to and extending from this holder is a stylus bar 4. Said bar is shaped to bridge around the marginal portion of the sound

box, as at 5 and has a straight extension 45 bearing against the diaphragm 2 and extending from a point near the margin of the diaphragm to a point slightly past the center thereof. The extension of the bar is radially disposed and is attached to the diaphragm in any manner desired, as by means of rivets 6.

It is a well known fact that the central portion of a diaphragm is the most sensitive to vibrations and when the vibrations 55 are very weak only this central portion will be vibrated if the stylus bar is connected to the center of the diaphragm, as ordinarily. Consequently the volume of sound is slight. By extending the stylus bar radially along the diaphragm and securing it thereto, said diaphragm is vibrated from the center to a point close to the periphery whenever the bar is vibrated and, therefore, 60 a greater volume of tone and a purer tone 65 is produced than would be possible with the ordinary mounting of the stylus bar on the center of the diaphragm.

What is claimed is:—

A phonograph sound box including a diaphragm, a stylus holder, a bar fixed to and extending from the holder, said bar having a straight portion bearing throughout its length against and extending radially along the diaphragm from a point adjacent the center thereof and thence across the center to a point adjacent the periphery of the diaphragm, and means for securing said straight portion to the diaphragm.

In testimony that I claim the foregoing 80 as my own, I have hereto affixed my signature in the presence of three witnesses.

DANA BERG.
